CLAIM

The ornamental design for a multi-purpose wall-mountable equipment holder with elastic restraint, as shown and described.

DESCRIPTION

FIG. 1 is a perspective view of a multi-purpose wall-mountable equipment holder with elastic restraint showing my new design therefor. The broken line drawing representing a rod-like article is for illustrative purposes and forms no part of my design;

FIG. 2 is a front elevational view with the elastic restraint released to show the design features of the restraint channel;

FIG. 3 is a rear elevational view;

FIG. 4 is a top plan view;

FIG. 5 is a left side elevational view, the right side elevational view being a mirror image thereof; and,

FIG. 6 is a bottom plan view.

The partial showing of the cross-hatched shading on the elastic restraint is understood to cover the entire surface.
